ATTORNEY

UNITED STATES PATENT OFFICE.

OTIS W. WARD, OF AUGUSTA, ARKANSAS.

BACK-BAND BUCKLE.

1,279,797.

Specification of Letters Patent. Patented Sept. 24, 1918.

Application filed April 10, 1918. Serial No. 227,723.

To all whom it may concern:

Be it known that I, OTIS W. WARD, a citizen of the United States, residing at Augusta, in the county of Woodruff and State 5 of Arkansas, have invented certain new and useful Improvements in Back-Band Buckles, of which the following is a specification.

The primary purpose of the present invention is to save time in the adjusting of 10 harness and in the maintaining of the same in proper working position.

A further purpose of the invention is the provision of a buckle which will maintain a given position and prevent slipping or 15 displacement of the traces when the latter are slackened as when backing or from other causes usually resulting in the traces having free movement.

The invention also has for its object to 20 provide a back band buckle which may be easily applied and which may be reversed to present a new supporting hook in the event of the hook engaging the trace becoming disabled from wear or any other purpose.

25 The invention furthermore has for its object the provision of a back band buckle which embodies a plurality of clamps and which are connected for simultaneous operation upon manipulating a single part.

30 The drawing illustrates a preferred embodiment of the invention. However, it is to be understood that in adapting the same to meet different conditions, various changes in the form, construction, and operation of the 35 invention may be resorted to without departing from the nature of the invention as claimed hereinafter.

In the drawings:—

Figure 1 is a top plan view of a back 40 band buckle embodying the invention, the dotted lines indicating a portion of the back band.

Fig. 2 is a transverse section on the line 2—2 of Fig. 1.

45 Fig. 3 is a detail view of a portion of one of the clamps.

Corresponding and like parts are referred to in the following description and indicated in all the views of the drawings by 50 like reference characters.

The buckle preferably comprises a plate 1, the same having a central portion omitted to provide an enlarged space 2. The sections or parts of the plate separated by 55 the space 2 are connected at their ends by means of elements 3 which are relatively

narrow and constitute bars. The plate or main frame of the buckle is provided near its opposite longitudinal edges with parallel slots 4 through which the back band is 60 passed, as indicated most clearly by the dotted lines in Fig. 2.

Hooks 5 are located at opposite longitudinal edges of the plate or buckle frame and preferably constitute a part thereof, said 65 hooks being centrally disposed. Keepers or mousings 6 close the spaces leading to the hooks 5, thereby preventing disengagement of the traces from the hooks when engaged therewith. The keepers or mousings 6 may 70 be of any structural formation such as commonly provided in snap hooks.

A clamp 7 is disposed at each side of the centrally disposed space 2 and is journaled at its ends in bearings 8 at the ends of the 75 bars or connecting elements 3. The clamps 7 are each formed of a strip which is bent into angular form between its longitudinal edges, one of the wings of the clamp being toothed, as shown in Fig. 3, so as to make 80 positive engagement with the back band and prevent relative slipping of the parts. An operating member 9 projects from each of the clamps 7 and is of loop form. A link 10 engages the operating members 9, and a ring 85 or like element 11 is applied to the link 10 to be engaged when it is required to simultaneously operate both clamps to effect release thereof from the back band. When moving the clamps into active engagement 90 with the back band pressure is applied to the link 10 whereby the clamps assume the position indicated most clearly in Fig. 2.

When the back band indicated by dotted lines in the figures of the drawing is applied to the buckle, it is trained through the several slots 4 and is engaged by the toothed edges of the clamps 7. This prevents any possible slipping of the buckle on the back band. The traces are engaged with the 100 hooks 5 in a manner well understood, and in the event of one of the hooks becoming disabled, the buckle may be reversed so as to bring the opposite hook into position to receive the trace. This applies to cases where 105 only one hook of the back band buckle is in operation at a time.

The foregoing description and the drawings have reference to what may be considered the preferred or approved form of my 110 invention. It is to be understood that I may make such changes in the construction,

arrangement, and combination of parts, materials, dimensions, et cetera, as may prove expedient and fall within the scope of the appended claims.

5 Having thus fully described my invention, what I claim as new and desire to secure by Letters Patent, is:—

10 1. A back band buckle provided with a plurality of clamps, and connecting means for operating the clamps simultaneously.

15 2. A back band buckle provided with a plurality of clamps, and a link forming connecting means between the clamps whereby the same are adapted to be operated simultaneously.

30 3. A back band buckle, comprising a plate or frame having a centrally disposed space, and clamps arranged along the edges of such space and connecting means between the clamps to admit of simultaneous operation thereof.

4. A back band buckle comprising a frame having oppositely disposed hooks and intermediate slots for the training therethrough of the back band, clamps for engaging the back band, and operating means for simultaneously actuating the clamps. 25

5. The herein described back band buckle, comprising a plate having a central portion omitted to provide a space and provided near opposite edges with parallel slots and having opposed hooks, clamps at opposite sides of the centrally disposed space, and means connecting the clamps for simultaneous operation. 30 35

In testimony whereof I affix my signature in presence of two witnesses.

OTIS W. WARD.
